[57] CLAIM

The ornamental design for a combined gemstone and setting, as shown and described.

DESCRIPTION

FIG. 1 is a top plan view of a combined gemstone and setting showing my new design;

FIG. 2 is a front elevational view, the rear view being a mirror image;

FIG. 3 is a side elevational view, the opposite side view being a mirror image;

FIG. 4 top left side perspective view;

FIG. 5 is a top left side perspective view shown in a position of use, the broken line showing of a partial finger ring is for illustrative purposes only and forms no part of the claimed design;

FIG. 6 is a front elevational view shown in a position of use, the broken line showing of a tether and attachment loop is for illustrative purposes only and forms no part of the claimed design;

FIG. 7 is a top plan view of a combined gemstone and setting showing a second embodiment of my new design;

FIG. 8 is a front elevational view of FIG. 7, the rear view being a mirror image;

FIG. 9 is a side elevational view of FIG. 7, the opposite side view being a mirror image;

FIG. 10 is a top plan view of a combined gemstone and setting showing a third embodiment of my new design;

FIG. 11 is a side elevational view of FIG. 10, the opposite side view being a mirror image;

FIG. 12 is a front elevational view of FIG. 10, the rear view being a mirror image;

FIG. 13 is a front, top left side perspective view of FIG. 10;

FIG. 14 is a top plan view of combined gemstone and setting showing a fourth embodiment of my new design, the side views not shown, are like those in FIGS. 11 and 12; and, FIG. 15 is a top plan view of a combined gemstone and pendant showing fifth embodiment of my new design, all side views not shown, are like those in FIGS. 11 and 12.

The bottom views, not shown, are not part of the claimed design.
